KIER

Eliezer A. Rusden, Nayatt, and Kenneth S. Johnson, Saylesville, R. I., assignors to The Textile-Finishing Machinery Company, Providence, R. I., a corporation of Rhode Island

Application May 13, 1930. Serial No. 451,894

9 Claims. (Cl. 8—19)

This invention relates to kier or like apparatus for treating or boiling textile fabrics, in the process of finishing; and has for its object to provide a construction which will afford a gentle circulation of the treating liquor about and through the work without causing channeling.

A still further object of the invention is to provide a circulation of the liquor by means of affording different densities therein as result of application of heat and without the action of mechanical moving parts.

A still further object of the invention is the provision of the heating means in such a location that the heat will be more effective and radiation from parts outside of the liquor will be reduced.

A still further object of the invention is to provide in the heating chamber a large heating surface with relation to the volume of liquor contained therein to cause a more violent action within the heating chamber.

A still further object of the invention is the provision of means for increasing the circulation without dilution of the liquor for treating the work.

A still further object of the invention is the provision of a system by which the steam which is formed in the kier compartment will be utilized to increase the circulation of the liquor therein.

A still further object of the invention is to provide an application of the heat so that the same will come in contact with the liquor and will not come in direct contact with the work which is being treated.

A still further object of the invention is to construct the apparatus to occupy but the minimum amount of floor space and cause all of the parts to be contained within the treating compartment.

With these and other objects and advantageous features in view, the invention consists of a novel arrangement of parts more fully disclosed in the detailed description following, in conjunction with the accompanying drawings, and more particularly set forth in the appended claims.

45 In the drawings:

Fig. 1 is a sectional view through the kier;

Fig. 2 is a sectional view on the line 2—2 of Figure 1, looking in the direction of the arrows;

Fig. 3 is an enlarged sectional view of the injector and a fragmental portion of the pipes connected thereto;

Fig. 4 is a side elevation of the kier partly broken away to show the goods and liquor therein.

In the use of kiers at finishing plants for textile fabrics, it is common to use motors and pumps to

circulate the liquor through the kier, which liquor is heated from without the kier and conducted thereto, or which liquor is heated by the direct injection of steam which causes a dilution of the liquor or in some cases the heating means are placed directly in the working chamber and care must be taken to protect the goods from burning by coming in direct contact with the heating means. Where pumps are so used to force the circulation, channeling is apt to occur by which the goods become separated to leave direct paths to permit passage of the liquor rather than causing the liquor to take a path through and about the goods as is desired, and in order to avoid these undesirable results mentioned, we have constructed a kier with a central heating chamber which causes the liquor to be heated and thereby raised in this chamber and dispensed out of the top thereof to settle down through the work which is usually several tons of cotton cloth and thus have its action upon this work, thus causing a circulation with no mechanical moving parts and no dilution of the liquor and as the heating is enclosed within a chamber, the work does not come in direct contact with the heating means, and if we desire, we may also utilize the steam formed above the liquor for increasing this circulation by conducting the steam from above the liquor to the lower part of the heating chamber where it is there injected; and the following is a detailed description of the present embodiment of this invention illustrating the preferred means by which these advantageous results may be accomplished:

With reference to the drawings, 10 designates a kier here conveniently shown as of cylindrical shape having a top portion 11 and neck 12 and a bottom portion 13 upon which the working parts are suitably mounted. A grating or platform 14 is provided spaced from the bottom 10 upon which the work to be treated in the compartment 15 is packed in the usual manner until several tons or the desired amount are loaded thereto. This cloth is distributed in different directions, zigzag, crossways, etc., in order to cause the treating liquor to pass through and about it and contact with all its portions in the movement of the liquor in the kier.

A central chamber 16, which we have here illustrated as cylindrical in shape is formed by a tubular shell 40 removably mounted within the compartment 15 by means of bolts 41 extending through the flange 42 and entering the rigidly mounted base portion 43 and into which central chamber the liquor may flow through many suit-

able openings such as 17 in this base portion. This chamber extends short of the height of the compartment 15 and is desired to be slightly above the normal level 48 of the liquor contained in the compartment 15 when a boiling is desired but the liquid will be above the top of this chamber when circulation is to be obtained without boiling. Within this chamber there is provided a plurality of pipes 18 each of which lead upwardly from the pocket 19 supplied by conduit 20 and thence downwardly as at 21 to a similar pocket 22 which is exhausted through pipe 23 to afford a means for supplying any suitable fluid-heating means, steam being used as a convenient supply for the purposes of this invention. The conduits 18, 21 occupy a large portion of the space of the chamber 16 and consequently a comparatively small volume of liquor is contained therein and will be quickly heated by contact with the large area of heating surface to cause a violent boil and discharge of the liquor by striking against a baffle plate 24 and being dispersed through the openings 25 into the liquor in the compartment 15 to settle down through the work 50 and again be received within the chamber 16 to be again heated and continue its circuitous path just described.

The liquor in the compartment 16 may be heated sufficiently to form steam which collects above the level of the liquor and may be conducted from above the liquor level by means of a conduit 26 downwardly through shut off valve 27 and through the injector 28 to the nozzle 29 and thus driven into the central chamber 16 to increase the heat and circulating movement of the liquor therein. Thus the steam which is formed from the liquor itself, is transferred back to the liquor thereby eliminating any dilution thereof. The valve 27 of course, will be closed until sufficient steam is generated to permit this action to take place.

The injector is of the usual type with Venturi necks 29 and 30 and is connected to the liquor as at 31 for the liquor suction. Whenever the steam, as above described is used, it is, of course, necessary to seal the opening 32 in the neck 12 by suitable cover provided for that purpose. However, where heat is not sufficient to form steam a cover is not required.

In some cases, it is desired to more quickly circulate the liquor and cause the large volume of work and liquor to boil, as at the start of the operation, in which case steam from an outside source may be injected through the conduit 33, shut off valve 34 and nozzle 35, which is similar to the nozzle 29, directly into the liquor, in which case the liquor will be mixed more concentrated than is finally desired to counteract the dilution of the steam.

There are no metal moving parts in the operation of the kier constructed as above disclosed, the circulation is caused by difference in density of the liquor when the level is above the heating chamber or by boiling the liquor and causing it to be thrown against the baffle plate and permitting it to settle again through the cloth or work to be acted upon. The heat supplied is entirely contained within the work compartment of the kier. Radiating losses are reduced and yet the work is protected from direct application with the heating pipes 18 and 21 by the tubular shell 40 which also serves to form a chamber for setting up a circulation of the liquor; and further by the operating means being entirely contained within the compartment a saving of floor

space, electric motors, engines and pumps is accomplished, and the heating and circulating may be maintained without dilution of the liquor.

Further, the construction is such that globules of steam forming about the steam pipes 18 and 21 or any entrained air or gases in the liquor of the chamber are afforded an easy path of rise or escape. Likewise, any air or gases entrained in the goods acted upon may in a similar manner escape upwardly to the space above the liquor, whereby a greater efficiency is obtained and as the circulation is of a milder degree, no channeling will be caused to prevent proper action of the liquor upon the work.

The liquor is usually supplied through the conduit 36 at the bottom of the kier and tends to cause the work 50 to rise, which is prevented by chains 37 shackled in one of the openings 38 in the angle irons 39 extending along the side of the cylinder 10. The chains are connected at their center to a ring 44 which has a free movement along the chamber 16 and hold the work 50 below the level 48 of liquor therein.

While we have described certain construction forms which embody the principles of our invention, it is obvious that other desired changes in arrangement may be made within the spirit and the scope of the invention as defined in the appended claims.

We claim:

1. In a kier, a compartment for receiving the work and treating liquor, a chamber within said compartment having communication with said compartment for the flow of liquor thereinto, conduits in said chamber, means for supplying heating fluid to said conduits to heat the liquor in said chamber and cause a circulation of the liquor through the work, an injector for said liquor communicating with the bottom of said chamber, and a conduit connected to the top of the compartment and leading to the bottom thereof for conducting steam from the top of the liquor to the injector.

2. In a kier, a compartment for receiving the work and treating liquor, a chamber within said compartment having communication with said compartment for the flow of liquor thereinto, conduits in said chamber, means for supplying heating fluid to said conduits to heat the liquor in said chamber and cause a circulation of the liquor through the work, and injecting means for said liquor communicating with the bottom of said chamber, and a conduit connected to the top of the compartment and leading to the bottom of the chamber for conducting the steam at the top of the liquor to the injecting means to increase the circulation of the liquor.

3. In a kier, a compartment for receiving both work and treating liquor, a central chamber in said compartment communicating with the upper portion of the compartment, a heating element in said chamber, means for injecting and extracting a heating fluid from the lower end of said element, an inlet conduit communicating the lower portion of the compartment with the lower portion of the chamber, said chamber being removably mounted in the compartment, treating liquor in said inlet conduit, whereby the chamber may be removed from the upper end of said element without disturbing said element.

4. In a kier, a compartment for receiving work and treating liquor, a central chamber in said compartment communicating with the upper and lower portions of the compartment, a casing for heating fluid positioned in said compartment be-

- low said central chamber and having an inlet and an outlet section, inlet and outlet conduits respectively communicating with said sections, and heating conduits connecting said sections 5 and positioned within said central chamber.
5. A method of circulating treating liquor through work in a kier, including heating a central portion of the volume of the liquor to produce circulation of the treating liquor and to 10 generate steam, and injecting the generated steam into the central portion of the liquor to increase the flow velocity thereof.
6. In a kier, a compartment for receiving work and treating liquor having a central loading 15 opening in its top wall, a heating unit centrally located in said compartment comprising a chamber communicating at its upper end and lower end with said compartment and of a height less than that of said compartment, a plurality of 20 pairs of tubes in said chamber, means for connecting the pairs of tubes at their upper ends injecting means connected to one of each of said pairs of tubes at its lower end and a discharge conduit connected to the other of each of said 25 pairs of tubes at its lower end, whereby steam may be injected into one of said tubes at its lower end to pass up said tube and down another tube connected therewith whereby the inlet and exit of said steam is from the lower end of said 30 chamber.
7. In a kier, a compartment for receiving work and treating liquor, a plurality of steam conduct- 35
- ing heating tubes centrally located in said compartment and supported and connected at their lower end only, a hollow tubular member embracing said tubes means for communication between said compartment and member at the upper and lower ends of said member, and means for independently mounting said member for removal from said tubes without disturbing said tubes. 40
8. In a kier, a compartment for receiving work and treating liquor, a heating unit centrally located in said compartment comprising a chamber communicating with said compartment at its upper end and provided with a plurality of hollow arms extending laterally from said unit thru which the chamber communicates with the compartment at its lower end and so arranged that circulation in said compartment is more evenly maintained. 45
9. In a kier, a compartment for receiving work and treating liquor, a heating unit centrally located in said compartment comprising a chamber communicating with said compartment at its upper end and provided with a plurality of hollow arms extending laterally and downwardly to a point adjacent the bottom of said compartment thru which the chamber communicates with the compartment at its lower end and so arranged that circulation in said compartment is more evenly maintained. 50
